UNITED STATES PATENT OFFICE

THEODORE A. SMITH, OF RIDGEWOOD, NEW JERSEY, ASSIGNOR TO RADIO CORPORATION OF AMERICA, A CORPORATION OF DELAWARE

TELEVISION SYSTEM

Application filed July 19, 1929. Serial No. 379,385.

The present invention relates to television systems, and, in particular, to television systems adapted for use in connection with the television transmission of motion picture films and the like.

In connection with motion picture films, it is well recognized in the art that the standard film which is provided for projection in motion picture houses is usually formed from a series of distinct frames which are separated from each other by a definite frame line, and in case of television transmission of such types of subjects where the usual spiral or mirror disk is used, it is noticed that objectionable effects are produced at the receiver in that the frame line must always be reproduced during each step by step motion of the film with respect to the analyzing system, assuming, of course, that a spiral disk scanning system is used. Also, if a scanning disk in which the apertures or lenses therein are arranged in a circle and the motion picture film is continuously fed forward with respect to the scanning element so as to produce the relative motion therebetween, as in the case of continuous feed transmission systems, the frame line is likewise found to exist in the received picture.

Therefore, as a principal object of my invention, I have sought to provide a method and means by which the objectionable effects of transmission of the frame lines and the like on motion picture films may be avoided.

Other objects of my invention are to provide a novel scanning element for accomplishing the elimination of the frame line between successive frames of motion picture films for television transmission so that only the picture area of the transmitted subject matter is analyzed.

Still other objects of my invention are to provide a scanning element for use in connection with television systems adapted to transmit motion picture films which is readily adaptable to the present known types of

existing apparatus utilizing, for example, the continuous feed type of motion picture film apparatus, without the need of transmitting the frame line, or even the outermost portion of the film including the edge portion having the drive sprocket holes, or the sound track portion adjacent the picture.

Other objects of my invention are to provide a scanning element for television systems adapted to transmit motion picture films, and the like, which is relatively simple in its construction and arrangement, one which is easy to manufacture, convenient to install, and highly efficient in its use.

Still other objects and advantages of my invention will hereinafter appear from a consideration of the following specification and claims in connection with the accompanying drawing, wherein:

Fig. 1 illustrates in a schematic manner a system utilizing the specialized type of scanning element which I have developed; and,

Fig. 2 illustrates, in an enlarged detail, further embodiments of the scanning element.

Now referring to the drawings, I have shown a motion picture film 1 adapted to be wound upon a pair of reels 3, and a motor 5 provided with a shaft or spindle 7 adapted to drive through an appropriate gear reduction system 10 a pair of sprocket wheels 9. The sprocket wheels 9 are arranged to rotate in the sprocket holes 11 provided on the outside edges of the motion picture film 1, and where a constant speed or synchronous motor is provided and where the motion is properly synchronized so as to rotate at a uniform rate, the motion picture film may thus be continuously fed forward at a substantially constant speed.

Removed from the motion picture film 1 and behind the same, I have provided a light source 13 which may be either of the incandescent or arc type, or any other desirable type, and arranged to project the light beams

50

issuing therefrom through a lens system 15 so as to focus the light beams issuing therefrom upon a scanning disk 17. The scanning disk 17, in accordance with my invention, is 5 preferably formed as a spiral in which the successive apertures or lenses 19 thereof appear to be arranged substantially along a circular path, because the pitch of the spiral is very slight and is only an amount equal 10 to the width of the frame line between successive picture frames or elements forming the entire motion picture film as is more particularly shown by Fig. 2 of my drawings. Thus, if it is assumed that the disk element 15 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540

Now, if it is considered that all of the apertures or lenses in the scanning disk as far as the last lens or aperture thereon in the spiral pass before the lens system 21 so as to project the light from the source as a point on the film, it will be noted that when light passes through the last aperture or lens *c* of the series of apertures or lenses in the scanning disk that the path traced on the disk will correspond to a point just beneath the frame line thereon, and that if the holes in the disk were arranged along a circular path that the next line on the film which would be traced would be the frame line, but since the pitch of the spiral is equal to the width of the frame line, after the entire frame of the film has been transmitted and the picture effectively jumps the frame line, it will be seen that the process of scanning the motion picture film 55 frame will be repeated, with the omission of any scanning period as regards the frame lines and the like.

For the purpose of projecting the light issuing through the apertures or lenses in the disk, I have provided a lens 21 so as to focus the light from the disk as a point source upon the film, and directly behind the film, I have provided a photoelectric cell or member 23 which electrically responds by an amount proportional to the varying intensities of

light and shadow on the film so as to produce modulation of a transmitter in accordance with the current flow through the cell, and thus vary the same directly in accordance with the intensity of light and shadow on the film itself. 70

The photo cell may be connected through an appropriate form of amplifier and arranged to have its output modulate a radio or wire transmitter, or the like, so that energy 75 may be transmitted to a distinct point, at which it may be received and properly amplified and arranged to actuate a glow lamp, or the like, which will produce light intensities at the receiving point corresponding and 80 proportionate in value to the intensities of light and shadow on the transmitted motion picture film.

As I have shown in the accompanying drawing, in order to provide an arrangement 85 such that the picture portion only of the film may be scanned, I have provided a mask 28 inserted between the lens 21 and the film 1. This mask is of particular use in cases where the film 1 is accompanied by a sound record 90 30 placed directly thereon and the mask may be of any appropriate rectangular size preferably to correspond with the individual frames of the picture such that the light beam focused upon the film through the lens 21 and caused to trace a path transverse thereto will also strike such portions of the film as carry picture representations. Also, where desired, instead of placing the mask between the lens 21 and the film 1, it is also fully within 100 the scope of my invention to place the mask before the photo cell condenser lens so as to screen the cell from all portions of the film other than the individual picture frames. The aperture of this mask need only be 105 slightly higher than the width of a beam of light from a single scanning aperture but should be of such a width that the scanning spot cannot impinge upon the sound track at one side of the film nor beyond the edge of 110 the picture frame at the other side.

Also, as has been suggested in my copending application, Serial No. 379,384, filed July 19, 1929, where it is desired to transmit motion picture film having the sound accompaniment directly thereon as is indicated by the sound track 30, I may provide a suitable sound head arrangement for converting the sound impressions placed upon the record into electrical impulses, as has been shown 115 in the above named copending application. In such a case, where desired, I may also transmit the sound accompaniment directly with the transmission of the picture through appropriate means fully disclosed in the said 120 copending application.

By Fig. 2, I have more particularly illustrated my scanning disk. By Fig. 2, I have shown several of the apertures or lenses extending about the disk wherein *a* designates 125

the first of the series and *c* the last of the series. The path *b* indicates a path corresponding to a circular spacing and positioning of the apertures and the amount of spiral pitch which I actually impart in the 360° to the lenses or apertures is indicated by the height of the spiral which is shown by the letter *d*. The width *d* as diagrammatically shown is intended to indicate the width of a frame line or distance between two component frame lines 25 on the motion picture film 1.

In order to receive pictures or visual reproductions of films transmitted by the arrangement herein set forth, I provide at the receiver, a corresponding scanning disk arranged to cooperate with the light producing element so as to rebuild the transmitted picture on a screen, or the like. However, at the receiving point, the disk may differ from the type at the transmitter, since the transmitter obtains a relative motion between the scanning disk and the scanned object or film by virtue of the fact that the film is continuously moved with respect to the scanning element having all apertures or lenses thereof along a path which is a very slight spiral and will substantially correspond to a circular path, but since at the receiver there is no means for imparting any relative motion between the source for rebuilding the light for illumination of a screen and the screen itself, I prefer to provide the usual type of Nipkow spiral disk for cooperation with a glow lamp, which may be either of the plate or point discharge type so that the received picture may be built up in the usual manner in a line for line manner in which the successive lines thereof are reproduced any predetermined and suitable number of times per second, of which number, 16 to 20, or 24, repetitions per second has been found to be satisfactory.

Other changes and modifications such as may readily suggest themselves to those skilled in the art will, of course, be the mirror disk having the successive mirrors thereon arranged in a path corresponding substantially to the arrangement of the successive apertures or lenses in the rotating scanning disk and arranged to cooperate with a continuously moving motion picture film projecting in any appropriate manner with respect to this type of scanning system, or, where desired, I may provide a fixed bank of mirrors and a smaller rotary scanning element of the mirror type or disk type for operating therewith, or I may provide a drum type scanning element with an internally arranged light source, without departing from the spirit and scope of my present invention.

Other changes and modifications will at once suggest themselves and become apparent to those skilled in the art to which the in-

vention relates, and, therefore, I desire to have my invention broadly construed and believe myself to be entitled to make any and all modifications of my invention such as fall fairly within the spirit and scope as defined by the hereinafter appended claims, wherein

I claim:

1. In a television system for transmitting motion picture film, means for continuously moving the film subject to be transmitted at a uniform rate of speed, and means for analyzing the picture portion only of the film.

2. In a television system for transmitting motion picture film, means for continuously moving the film subject to be transmitted at a uniform rate of speed, and means for analyzing the subject in such manner that the frame lines separating successive portions of the said film are omitted.

3. In a system for transmitting motion picture films having successive pictures thereon separated by a frame line on the film, means for moving the film subject to be transmitted at a constant and uniform rate of speed past a predetermined point, means for analyzing the varying intensities of light and shadow on the film subject and converting the said varying intensities of light and shadow into electrical variations, and means providing for the omission of the frame lines separating the successive pictures on the film from the analyzing process.

4. In a system for transmitting motion picture films having successive pictures thereon separated by a frame line on the film, means for moving the film subject to be transmitted at a constant and uniform rate of speed past a predetermined point, means for scanning said film in a line for line manner along a path traverse to the path of motion thereof, and means provided on said scanning means for interrupting the sequence of said lines of scanning to eliminate the frame lines separating the successive pictures on the film from the scanning path.

5. In a television system for transmitting motion picture films, a scanning device having a plurality of scanning elements arranged thereon, means for continuously moving the film relative to said scanning element at a uniform rate of speed, means provided by said scanning device for analyzing the film in a line for line manner during the relative motion of said film with respect thereto, and means provided by the scanning device for analyzing only the picture portion of said film record.

6. In a system for transmitting motion picture films by television, means for moving a motion picture film subject at a uniform constant rate of speed relative to a predetermined point, a scanning element, means provided by said scanning element for analyzing the intensity of light and shadow on said

- film subject, means for converting the varying intensities of light and shadow on the film subject into electrical energy variations, and means also provided by said scanning element for scanning the picture portion only of said motion picture film subject.
7. In a television system for transmitting motion picture films, a scanning device having a plurality of scanning elements arranged thereon, means for continuously moving a film subject to be transmitted relative to said scanning device at a uniform rate of speed, means provided by said scanning device for analyzing the film in a line for line sequence during the relative motion of said film with respect thereto, and means also provided by the scanning device for interrupting the sequence of said lines of scanning, whereby the scanning path passes over each frame line and scans the picture portion only of said film record.
8. In a system for transmitting motion picture films by television, a scanning device, means for moving a motion picture film subject at a uniform constant rate of speed relative to said scanning device, means provided by said scanning device for analyzing said film subject in a sequential line for line manner, means for converting the varying intensities of light and shadow on the film subject as determined by said line for line analyzing into electrical energy variations, and means also provided by said scanning element for interrupting the sequence of said lines of scanning as each complete picture frame is scanned so as to pass over the frame line separating successive pictures of the film and scan the picture portion only thereof.
9. In a television system for transmitting motion picture films, a rotary scanning element having a plurality of scanning elements arranged thereon in a spiral path having a pitch equal to the width of the frame line separating successive pictures on motion picture film to be transmitted, means for longitudinally advancing said picture film at a constant and uniform rate relative to said scanning element, means provided by said scanning element for scanning the film in a line for line manner during the relative motion of said film with respect thereto, and means provided by the scanning element for interrupting the sequence of said lines of scanning at periods when the frame lines on said film would normally follow the scanning in line for line sequence, whereby the picture portion only of said film record is scanned.
10. A scanning device for use in the television transmission of motion picture films comprising a rotatable member having a plurality of scanning elements arranged thereon in such manner as to scan the picture portion only of the said motion picture film.
11. A scanning device for use in connection with the television transmission of motion picture films having the successive picture frames separated by a frame line which comprises a rotatable scanning member having a plurality of scanning elements arranged thereon in a spiral path having a pitch equal to the width of the frame line on the said film.
12. A scanning device for use in the television transmission of motion picture films having the successive picture frames separated by a framing line which includes a disk member having a plurality of scanning elements arranged about the surface thereof in a spiral path having a pitch equal to the width of the frame line on the said film.
13. In a television system for transmitting motion picture films, a scanning device having a plurality of scanning elements furnished thereon, means for continuously moving the film relative to said scanning device at a uniform rate of speed, means provided by said scanning device for analyzing the film in a line for line manner during the relative motion of said film with respect thereto, a photoelectric element for converting variations in intensity of light and shadow on the film as determined by the scanning action into varying electrical currents, and a mask interposed between said scanning device and said photoelectric element for limiting the response of said photoelectric element to the variations in light and shadow on the picture frame portion only of said film.
14. The method of analyzing motion picture films having frame lines separating successive picture frames thereof for television transmission which consists in continuously and uniformly advancing the film relative to a predetermined point, and in analyzing the film in such manner as to analyze the picture portion only thereof.
15. The method of transmitting motion picture films having the successive picture frames thereon separated by frame lines which consists in continuously and uniformly moving the film relative to a predetermined point, and in analyzing the varying intensities of light and shadow on the successive picture frames in such manner that the frame lines separating successive picture frames are omitted from the analyzing process.
16. The method of electrically transmitting motion picture film having the successive picture frames thereof separated by a frame line which consists in continuously and uniformly moving the film relative to a predetermined point, in analyzing the varying intensities of light and shadow on the film frames, in converting the varying intensities of light and shadow on the film surface into varying electrical energy pulses, and in omitting from the analyzing process the frame lines separating successive picture frames of the film.
17. The method of electrically transmitting motion picture films having the successive picture frames separated by a frame line which includes a disk member having a plurality of scanning elements arranged about the surface thereof in a spiral path having a pitch equal to the width of the frame line on the said film.

ting motion picture film having the successive picture frames thereof separated by a frame line which consists in continuously and uniformly moving the film relative to a predetermined point, in analyzing the varying intensities of light and shadow on the film frames, in converting the varying intensities of light and shadow on the film surface into varying electrical energy pulses, in omitting from the analyzing process the frame lines separating successive picture frames of the film, and in limiting the conversion of varying intensities of light and shadow on the film into electrical energy pulses to picture portions only of the film.

THEODORE A. SMITH.

ting motion picture film having the successive picture frames thereof separated by a frame line which consists in continuously and uniformly moving the film relative to a predetermined point, in analyzing the varying intensities of light and shadow on the film frames, in converting the varying intensities of light and shadow on the film surface into varying electrical energy pulses, in omitting from the analyzing process the frame lines separating successive picture frames of the film, and in limiting the conversion of varying intensities of light and shadow on the film into electrical energy pulses to picture portions only of the film.
